LOCK

Walter B. Goughnour, Seattle, Wash.

Application April 29, 1946, Serial No. 665,841

2 Claims. (Cl. 292—159)

1

This invention relates to door locks, and it has reference more particularly to improvements in locks of a type adapted for use with doors of automobiles and similar vehicles, and whereby doors equipped with such locks will be held tightly in closed position until the lock releasing mechanisms are manually actuated for this purpose.

It is the principal object of this invention to provide a door lock of the above stated kind whereby a door may be held securely and tightly closed against any possibility of being released by direct pressure applied against the door, and which automatically compensates for any looseness that may result from wear in the latching elements, and thus eliminates rattling, looseness and all feeling of insecurity of the lock.

Another object of the present invention is to provide a door lock wherein the locking elements are characterized by an over-running clutch gear in combination with a gear toothed bolt, that are engaged by the closing of the door, and which can only be disengaged for opening the door, by retraction of the bolt.

Another object of the invention is to provide a lock with a novel safety latch mechanism that operates in conjunction with the manual release member.

Still further objects of the invention reside in the details of construction of the various parts of the lock, in their combination and mode of operation, as will hereinafter be fully described.

In accomplishing these and other objects of the invention, I have provided the improved details of construction, the preferred forms of which are illustrated in the accompanying drawings, wherein—

Fig. 1 is a view, in side elevation, of a portion of an automobile, showing a door that is equipped with a lock embodying the features of the present invention therein.

Fig. 2 is an enlarged, horizontal section of the lock, taken on line 2—2 in Fig. 1.

Fig. 3 is a section of the lock as seen on line 3—3 in Fig. 2.

Fig. 4 is a sectional detail of one of the clutch rollers and associated parts.

Referring more in detail to the drawings—

In Fig. 1, 10 designates what may be a side wall portion of an automobile and 11 designates a door that may be hinged to the wall in such manner as to swing to and from a closed position. As observed in Fig. 2, the side wall 10 has a substantial horizontal thickness, as defined by its inner and outer wall members 12 and 13, and the

door 11 is of like thickness as defined by its inner and outer wall members 14 and 14'.

The door, as here shown, is limited in its extent of closing, by an edge flange 15x thereon, adapted to engage against an inset shoulder 14x that is formed along the opposing edge of the doorway, as observed in Fig. 2. A cushioning strip C is applied to the inside of the flange 15x and, at the opposite side of the doorway, the door is adapted to close in contact with a flexible joint sealing strip S of a suitable kind.

It is desired to here explain that the present lock is well adapted to various uses other than with doors of automobiles, for example, it is suitable for use on refrigerators, cupboards, and like articles and well adapted also for use with airplane doors, and, in fact, all doors that are hinged at one edge to swing into a doorway against a closing stop.

As observed best in Fig. 2, the present lock comprises a rigid and substantial housing 15 that is fixed in the wall 10, or door frame, between its inner and outer members and flush with the doorway, or opening in the wall to which the door is applied. As seen in Fig. 3, the lock housing 15 has a vertical edge flange 16 through which screw bolts or the like, as at 17, are extended through the wall members 18, as in Fig. 3, to secure the housing in place. Also, the housing

15 is here shown as being made in disconnectable upper and lower parts, to facilitate the assembly therewith of the contained lock elements. These parts are held together by screw bolts, as at 19.

Formed in the housing 15 is a gear wheel chamber 20 in which a gear toothed wheel 21 is revolvably contained. This gear is mounted to revolve on a vertically disposed hub 22 that is rigidly fixed in the housing by being solidly secured to the top wall member by a screw 23 as observed in Fig. 3; the hub being fitted in a socket that is bored in the gear wheel coaxial thereto. This gear wheel housing is open at one side and a toothed portion of the gear wheel, spanning an arc of about 90° extends from this opening into the doorway, as observed in Fig. 3.

In the arrangement of parts shown, the hub member serves as the stationary member of an over-running clutch of which the gear wheel is the rotary member.

As noted best in Fig. 2, the hub member of the gear is formed longitudinally with four equally spaced, outwardly opening recesses 25, in which clutch rollers 26 are contained. The base surfaces of the several recesses are similarly inclined toward the inner surface of the gear

and the rollers 26 are adapted to operate in the recesses and against said surfaces as clutch rollers to effect an interlock of hub and wheel whenever there is any tendency of the gear wheel to turn in a reverse direction; that is, in a direction that would permit the locked door to move from closed toward an open position. The several rollers are pressed yieldingly into their wedging or clutching positions by the pressure of small coiled springs 30 that are mounted in the hub; each to bear against a plate 31 pivoted in the hub and, in turn, bearing against the corresponding roller.

The gear wheel in this lock mechanism serves as a keeper member with which the locking bolt engages to hold the door in its closed position.

Mounted on the door, directly opposite the gear housing 15, is a housing 35. This is open at the end which faces the gear wheel. Slidably fitted in this housing is a locking bolt 38 which is yieldingly urged outwardly; that is, toward latching position, by a coiled spring 39 which is located within the bolt and bears at its ends against the inner end wall of the housing and against the base of a socket provided in the bolt. An anchor bolt 40 extends through a hole 42 that is bored axially through the locking bolt 38 and is threaded at its one end into the inner end wall of the housing 35. At its other end, the bolt has a head 43 contained in a counterbore in the bolt, and is designed to engage a shoulder 44 at the base of the counterbore to limit the extent to which the bolt may be extended by the spring.

On its outer end, the locking bolt 38 has a plurality of gear teeth 45 adapted to intermesh with the teeth of the clutch gear wheel when the door is closed, thus to lock the door in its closed position.

It is of significance to point out that the gear teeth 45 on the locking bolt are so formed as to correspond to an arcuate gear segment having the hinge axis of the door as the center. Thus, in the closing action of the door, these teeth can be made to properly mesh with the teeth of the gear without looseness or binding. If looseness should occur, then the bolt 40 may be adjusted to permit the bolt to extend farther and slack to be taken up.

For the manual withdrawal of the bolt to release the door, I have provided a lock handle member which comprises a cross shaft 50 that extends transversely through the door directly below the bolt housing 35 and which at its outer end has a hand lever 51 fixed thereon. Within the door, a lever 53 is fixed to the cross shaft, and the end of this lever is operable through a longitudinal slot 54 in the bottom wall of the housing and may be engaged against a shoulder 55 on the locking bolt 38 to retract it against the pressure of spring 39. A coiled spring 60 is attached to the housing 35 and to an arm 61 extended from the lever 53 to normally retain the swinging end of lever 53 in a position away from the shoulder 55, as in Fig. 3, to permit the locking bolt to be fully extended, as permitted by bolt 40.

While I have shown the present locking bolt 38 as being operated from its extended to its retracted position by the hand lever 51 through the intermediary of shaft 50 and lever 53, it is to be understood that other means for this purpose might be employed; for example, a push button type of lock release mechanism that could effect an application of retractive force against the shoulder 55.

It is understood also that a handle might be applied to the shaft 50 at the inside of the door, the same as at the outside, if such should be required or desired.

5 To insure against any possibility of the locking bolt being forced to a releasing position by outward pressure against the door, a safety latch pin 70 is slidably mounted in a vertical bore 71 through the bottom wall of the housing 35, in such position that the upper end of the pin will act as a stop that will prevent any retractive movement of the latch bolt except as produced by the hand lever. At its lower end, the pin 70 has a pin and slot connection, as at 80, with lever arm 61, so that, with the turning of the handle, this pin will be withdrawn from its bolt stopping position, and permit the bolt 38 to be retracted by the turning of the hand lever 51.

20 Any other suitable type of over-running clutch mechanism other than that shown might be employed with satisfactory results; for example, a simple pawl and ratchet device. However, the present type is desired because of its taking immediate effect as soon as the door stops moving in its closing direction.

With the parts so constructed and assembled, the operation of the lock is as follows:

Starting with the door at any open position, 30 when it is swung to closed position, as in Fig. 2, the teeth 45 of the locking bolt 38 will swing into mesh with teeth of gear wheel 21 and the wheel will rotate with the inward swinging movement of the door until the door comes to its closing limit. Under this turning action of the gear wheel, the clutch rollers roll freely. However, as soon as the turning action of the wheel stops, the clutch rollers take effect to prevent any back turning of the gear wheel and thus the door will 35 be retained tightly in its closed position.

To open the door, it is required that the locking bolt be retracted to disengage its teeth from the gear 21. To accomplish this, the handle lever 51 is turned, as indicated by the arrow thereon in Fig. 1, thus to turn the shaft 50 and withdraw the locking pin 70 from holding position and cause the lever arm 53 to engage the shoulder 55 of the bolt 38, thus to retract the locking bolt against the holding force of spring 39. Then the 40 door may be swung to open position.

Having thus described my invention, what I claim as new therein and desire to secure by Letters Patent is:

1. A door locking mechanism comprising a bolt 55 guide housing adapted for mounting in the swinging edge of a hinged door, a bolt slidably mounted in said housing and having a plurality of gear teeth on one end thereof adapted for intermeshing with a keeper member in the form of a one-way clutch gear wheel, spring means acting against the bolt and normally retaining the toothed end thereof extended from the housing, and manually operated means for retracting the bolt from the gear for opening the door; said gear teeth of the bolt being formed on a pitch circle that centers in the hinge axis of the door mounting the bolt, and an adjustable stop for determining the extended position of the bolt.

2. In a door locking mechanism of the character described, a guide housing for a locking bolt adapted to be mounted in a hinged door, a locking bolt mounted in the housing and movable endwise between extended and retracted positions and having a plurality of gear teeth at its outer 70 end adapted for engaging a keeper member in the

form of a rotatably mounted one-way clutch gear, a spring in the housing acting against the bolt to urge it to its extended position, a lock operating means comprising a shaft rotatably mounted in the housing, a handle for rotating the shaft and a lever fixed on the shaft and adapted upon its rotation to engage with the bolt to move it to a retracted position, said bolt having a hole lengthwise therethrough, and an adjusting bolt 10 extended through said hole and adjustably threaded into the housing and having a head engaged with the bolt to limit its extension under the pressure of said spring.
